UNITED STATES PATENT OFFICE.

WILLIAM W. EDWARDS, OF LOS ANGELES, CALIFORNIA.

DIRECTION INDICATOR FOR AUTOMOBILES.

Application filed May 20, 1924. Serial No. 714,590.

This invention particularly pertains to a signaling device of the type such as is employed on vehicles to designate to observers when the vehicle is about to turn to the right or to the left, or to come to a stop, and especially relates to the class of signals embodying a manually controlled swinging arm or semaphore.

An object of the invention is to provide a signaling device embodying a swinging semaphore arm with which is associated a series of finger-like blades adapted to be spread into a fan-like arrangement when the semaphore arm is disposed in an operative position, and adapted to be folded and concealed when the semaphore arm is in its normal or non-signaling position.

Another object is to provide a simple and efficient mechanism whereby the semaphore arm and the associated finger-like blades may be effectively operated.

Another object is to provide a means whereby the signaling element may be illuminated when in the signaling position in which the illumination will be controlled by movement of the signaling element.

With the foregoing objects in view, together with such other objects and advantages as may subsequently appear, my invention is illustrated by way of example in the accompanying drawings, in which—

Figure 1 is a view of the signaling device as seen in side elevation with the parts disposed in their normal non-signaling position.

Figure 2 is a view in side elevation showing the device as disposed in signaling "Stop".

Figure 3 is a view in side elevation showing the parts as disposed in signaling "Turn to the left".

Figure 4 is a view in side elevation showing the parts as disposed in signaling "Turn to the right".

Figure 5 is a view of the signal device as seen in elevation with parts removed showing the signaling element disposed in its non-signaling position.

Figure 6 is a view in elevation with parts removed, similar to that shown in Figure

5, showing the signaling element disposed in a signaling position.

Figure 7 is a detail in horizontal section as seen on the line 7—7 of Figure 6.

Figure 8 is a detail in section as seen on the line 8—8 of Figure 7.

Figure 9 is a detail in section as seen on the line 9—9 of Figure 8.

Referring to the drawings more specifically, 10 indicates a housing of box-like form, 60 one side of which is open as indicated at 11, and which embodies a back wall 12 and side walls 13 and 14 and top and bottom end walls 15 and 16. A semaphore arm 17 is pivoted on a shaft 18 to swing vertically 65 through the open side of the housing 10; the shaft 18 being disposed adjacent the upper end portion of the housing and extending transversely thereof with its end portions carried by the side walls 13 and 14. 70 The semaphore arm is adapted to be normally disposed in a depending position and then be located within the housing. The semaphore arm is formed with a U-shaped cross section, being provided with a front 75 wall 19, side walls 20 and 21, and a lower end wall 22. When the semaphore arm is in its dependent or vertical position within the housing 10, the side walls 20 and 21 extend parallel with the side walls 13 and 14 80 of the housing and the front wall 19 extends substantially flush with the outer edges of the housing side walls 13 and 14 so as to form a closure for the lower portion of the open side 11 of the housing.

85 Affixed to the side wall 21 of the semaphore arm and encircling the shaft 18 is a pinion 23 which meshes with rack teeth 24 on a slide bar 25, which bar is mounted for vertical reciprocal movement in a guide sleeve 26 mounted on the back wall 12 of the housing. The lower end of the slide bar is pivotally connected to a link 27 the lower end of which is pivotally attached to a crank 28 on a rock shaft 29, which rock shaft extends through the side wall 14 of the housing and is fitted with a lever arm 30 adapted to be manually operated to effect oscillation of the rock shaft and thereby impart longitudinal reciprocal motion to the slide bar. 100

The lever arm 30 is here shown as provided with a hand-hold 31 that carries a suitable catch indicated at 32 adapted to be detachably engaged with a series of apertures 33 in a segment 34 whereby the lever arm may be held in various positions.

Pivoted on the shaft 18 is a series of finger-like blades 35 indicated separately at *a*, *b*, *c*, and *d* which are adapted to be folded 10 to extend substantially parallel with each other within the semaphore arm when the latter is in its dependent non-signaling position and are also adapted to be spread into a fan-like arrangement when the signaling 15 arm is in a signaling position. The blades 35 are arranged adjacent the side wall 20 of the semaphore arm 17 and the outermost blade *a* is formed with a laterally projecting flange 36 against which slidably bears the outer end portion of a plate spring 37, the inner end of the spring being affixed to a standard or block 38 mounted on the front wall 17 of the semaphore arm. The spring 20 37 exerts a yieldable pressure against the blade *a* tending to rock the latter outwardly 25 relative to the semaphore arm.

The blades *a*, *b*, *c* and *d* are each formed with arcuate slots indicated at *e*, *f*, *g* and *h*, respectively, extending concentric with the 30 axis of the shaft 18, and mounted on the blades *b*, *c* and *d* are pins indicated at *i*, *j* and *k*, which extend into slots *e*, *f* and *g* on the blades *a*, *b* and *c*, respectively; and mounted on the side wall 20 of the semaphore arm is a pin *l* which extends into the slot *h* on the blade *d*. The pin and slot connections with the blades *a*, *b*, *c* and *d* serve as slidable connections between the adjacent blades, which will permit the blades 35 40 being positioned substantially parallel with each other in their folded position, and yet act on outward movement of the blade *a* relative to the semaphore arm under action of the spring 37 to successfully swing the arms *b*, *c* and *d* into various radial positions on the shaft 18 and into a substantially fan-like arrangement as shown in Figure 6.

Encircling the shaft 18 is an insulating block 39 which is affixed to the pinion 23 50 to turn therewith relative to the shaft 18, and carried on the insulating block is a contact member 40 adapted to be moved in and out of contact with a spring wiper 41 carried by the back wall 12 of the housing and insulated therefrom; the spring wiper contact 41 being connected to an electrical conductor 42 leading to one terminal of a suitable source of electric current supply, not shown, and the contact member 40 being 55 connected to an electrical contact 43 leading to an electric lamp 44 carried on the end wall 22 of the semaphore arm. One terminal of the lamp is grounded through the semaphore arm in such manner that when the contacts

40 and 41 are in contact an electric current 65 will be completed through the lamp to illuminate the latter. The contact 40 is so arranged that when the semaphore arm is in its depending position it will be out of contact with the wiper contact member 41 70 thereby breaking the electric circuit to the lamp; but when the semaphore arm is moved outwardly the contact member 40 will effect electrical connection with the wiper contact 75 41 to complete the electrical circuit through the lamp. The side walls 20 and 21 of the semaphore arm are formed with elongated openings 45 through which the light from the lamp emanates to either side 80 of the semaphore arm to render the movement of the latter in and out of the signaling position, clearly visible at night. The under side of the semaphore arm being open, a portion of the light from the arm 44 will be directed onto the blades 35 whereby the 85 latter will be rendered clearly visible at night.

Suitable means are provided for normally closing the front of the housing above the semaphore arm 17, irrespective of the position of the semaphore arm, which means is here shown as comprising a slide block 46 mounted to slide vertically in guide channels 47 and 48 formed in the inner faces of the side walls 13 and 14, respectively, of the 90 housing. The lower end of the slide block 46 normally seats on the upper end portion of the front wall 19 of the semaphore arm, as particularly shown in Figure 5, the slide block moving up and down in its guide channels together with the semaphore arm, on 95 operation of the latter.

When the semaphore arm is disposed in its depending position as shown in Figure 5, the blades 35 will extend substantially 100 parallel with each other within this semaphore arm and together with the latter will be concealed from view within the housing 10. The spring 37 will exert a pressure 105 against the blade *a* which in turn will bear at its outer or lower end against the back wall 12 of the housing, so that the spring 37 will act to assist the hand operated mechanism in effecting initial outward and upward movement of the semaphore arm. 110

In the application of the invention the housing 10 is mounted in a vertical position at a convenient point on a vehicle, being preferably arranged at one side of the vehicle as on the windshield frame of an automobile in such manner that the semaphore arm when actuated will swing laterally of the vehicle and project to one side thereof so as to be readily observed from the front and rear of the vehicle. 115

In the operation of the invention, when it is desired to signal that the vehicle equipped therewith is about to come to a stop, the 120

- rock shaft 29 is oscillated through the medium of the manually controlled lever arm 32, or in any other suitable manner, so as to cause the slide bar 25 to move downwardly and thereby effect rotation of the pinion 33, which, by reason of being fixed relative to the semaphore arm, will cause the latter to swing outwardly into an inclined position, as shown in Fig. 2, whereupon the operator brings the rock shaft to a rest and when so desired causes the semaphore arm to remain in its inclined position by holding the lever arm 30 against movement, as by engaging the catch 32 with the openings 33 in the segment 34. On initial operation of the shaft 29 the semaphore arm will be caused to move quickly from its normal stationary position by reason of the effort exerted by the spring 37 through the medium of the blade *a*. As the semaphore arm moves outwardly and downwardly the spring 37 rocks the blade *a* outwardly with respect to the semaphore arm and thereby causes the blades *b*, *c*, and *d* to successively move outwardly into their open or spread position as shown in Figure 6 through the medium of the pin and slot connections before described. The extent of the outward movement of the blades is limited by the pin *l* engaging the end of the slot *h* in the blade *d*. The blades will then be disposed in a fan-like arrangement, and will have an appearance similar to that of a human hand. As the semaphore arm moves outwardly into its normal position the electric lamp 44 is illuminated as before described.
- When it is desired to signal that the vehicle is to turn to the left the rock shaft 29 is actuated so as to cause the slide bar 25 to move a sufficient distance to move the semaphore arm into a substantially horizontal position as shown in Figure 3. When it is desired to signal that the vehicle is about to turn to the right the semaphore arm is moved to extend into an upwardly inclined position as shown in Figure 4.
- When it is desired to restore the signal element to the normal position, the catch 32 is released whereupon the semaphore arm will gravitate downwardly to its dependent position and in moving to its non-signaling position within the housing of the outermost blade *a* will be caused to impact against the back wall 12 of the housing and by reason of the yieldable pressure of the spring 37 thereon will effectively cushion the downward and inward movement of the semaphore and cause the latter to come to rest without noise or jar.
- While I have shown and described a specific embodiment of my invention I do not limit myself to the exact details of construction and arrangement shown but may employ such changes and modifications in the parts, and in the construction and arrangement of parts as may come within the spirit and scope of the appended claims.
- I claim—
1. In a signal device, a vertically swinging semaphore arm, a support therefor, means for rocking said semaphore arm, a series of pivotally mounted blades associated with said semaphore arm and movable relative thereto, means whereby said blades will be positioned substantially parallel with each other when the semaphore arm is in a depending position, means whereby rocking one of said blades relative to the semaphore arm will cause the remaining blades to successively move therewith, and spring means carried by said semaphore arm operable to effect movement of said blades on upward swinging movement of said semaphore arm.
  2. In a signal device of the character described, a supporting housing, a semaphore arm pivotally carried by said housing, a pinion affixed to said semaphore arm concentric with its axis of rotation, a slide bar carried by said housing having rack teeth meshing with said pinion, means for reciprocating said slide bar whereby oscillation of said semaphore arm will be effected, a series of blades pivotally mounted to swing from a common pivot adapted to be positioned substantially parallel to each other and also adapted to be spread into a fan-like arrangement, and a spring operable to effect movement of said blades relative to said semaphore arm when the latter is swung outwardly on its support.
  3. In a signal device of the character described, a housing having an open side, a semaphore arm pivoted in said housing arranged to swing through the open side thereof, a series of blades pivoted to swing on the axis of said semaphore arm adapted to extend substantially parallel to each other and with the semaphore arm when the latter is in a dependent position, a spring arranged to exert a yieldable pressure between one of said blades and the semaphore arm operable to swing said blade into inclined position relative to the semaphore arm when the latter is swung outwardly from its normal dependent position, and means whereby the movement of said spring actuated blade will effect successive movement of the other blades operable to position the blades in a fan-like arrangement.
  4. In a signal device of the character described, a housing having an open side, a semaphore arm pivoted in said housing arranged to swing through the open side thereof, a series of blades pivoted to swing on the axis of said semaphore arm adapted to extend substantially parallel to each other and with the semaphore arm when

the latter is in a dependent position, a spring arranged to exert a yieldable pressure between one of said blades and the semaphore arm operable to swing said blade 5 into inclined position relative to the semaphore arm when the latter is swung outwardly from its normal dependent position, means whereby the movement of said spring actuated blade will effect successive move-

ment of the other blades operable to position the blades in a fan-like arrangement, manually operated means for controlling and effecting movement of said semaphore arm, and means whereby said spring will co-act with said last named means in effecting initial movement of said semaphore arm from its normal dependent position. 10 15

WILLIAM W. EDWARDS.
